UNITED STATES PATENT OFFICE.

NATHANIEL ROE, OF PATCHOGUE, NEW YORK.

TAPE-REEL.

1,110,994.

Specification of Letters Patent. Patented Sept. 15, 1914.

Application filed October 16, 1913. Serial No. 795,421.

To all whom it may concern:

Be it known that I, NATHANIEL ROE, a citizen of the United States, residing at Patchogue, Suffolk county, in the State of New York, have invented certain new and useful Improvements in Tape-Reels, of which the following is a full, clear, and exact specification.

My invention relates to improvements in tape reels, and the same has for its object more particularly to provide a simple, efficient and reliable reel having a crank for winding up the tape, which crank is so constructed and arranged that when the tape is partly withdrawn from the casing the portion of the crank handle lying normally within the casing will be automatically projected outwardly therefrom.

Further said invention has for its object to provide a tape reel having a folding crank handle which is adapted to be fitted within the reel upon which the tape is wound, and means arranged within the casing which incloses the tape adapted to engage with the free end of the foldable portion of said crank handle, whereby to project the same outwardly from said casing in the course of the first revolution of the reel.

To the attainment of the aforesaid objects and ends, my invention consists in the novel details of construction, and in the combination, connection and arrangement of parts hereinafter more fully described and then pointed out in the claims.

In the accompanying drawings forming part of this specification, wherein like numerals of reference indicate like parts, Figure 1 is a face view showing one form of reel constructed according to, and embodying my said invention; Fig. 2 is a transverse section on the line 2—2 of Fig. 1; Fig. 3 is a face view of the casing with the tape and the reel therefor removed therefrom; Fig. 4 is an enlarged detail perspective view of the means for projecting the crank handle, the same being shown detached from the casings; and Fig. 5 is a detail, bottom view of the winding reel or drum detached from the casing.

In said drawings 10 designates the reel as a whole which comprises a closed, shallow, circular casing 11 having an opening 12 in its edge through which one end of the tape 13 with its attached ring or bail 14

normally extends. The casing 11 is provided in its top with a large centrally arranged opening 15 having an inwardly extending rim. The base of said casing is provided with an inwardly raised portion 17 having an opening 18 therein, and surrounding said central, raised portion 17 is arranged an annular member 16 which is soldered or otherwise suitably secured to the inner side of the base of the casing, and provided with a cam portion 19.

Within the opening 15 of the casing is loosely fitted a reel 20 comprising a top 21 having an annular flange 22 extending downwardly therefrom, and terminating in a horizontal plane slightly above the base of the casing. The reel 20 is provided upon its under side with a centrally arranged depending post 23 having an interiorly threaded opening in its lower end adapted to be engaged by a screw 24 whose head is disposed within the recessed central portion 17 of the base, in order to maintain said reel revolvably secured within said casing.

25 denotes a folding crank handle having one end pivotally secured upon the upper side of the reel 20, intermediate bearings 26, 26, arranged adjacent to the periphery of the reel. The free end of said crank handle 25 extends across the top of said reel and terminates at the opposite side of the reel at a point adjacent to the periphery, and is provided upon its under side with a handle or finger portion 27 which is revolvably mounted upon a fixed stem 28 which is adapted to extend through an opening 29 provided in the top of the reel.

30 denotes a spring finger which is struck up from the flange 22 of the reel, and is adapted to engage frictionally with the side of the handle or finger portion 27 when the said handle is fully folded within the reel 20, and the folding crank 25 is flat upon the top of said reel. The flange 22 is provided with one or more vertical slits or recesses 31, 31, to receive and hold the inner end of the tape 13 secured to said reel.

The operation of the apparatus is as follows: Assuming that the tape 13 is fully wound up upon the reel 20 it merely becomes necessary to grasp the ring or bail 14 and withdraw the tape. As the tape is withdrawn the reel 20 will be caused to revolve, and in the course of the first revo-

lution of said reel the inner end of the handle or finger portion will contact with the cam projection 19 of the annular member 16, and as the revolution of said reel continues the end of said handle or finger portion will ride up upon said cam projection 19 and cause said handle or finger portion to be freed of its engagement with the spring 30, and the free end of the 10 crank handle projected as shown at Fig. 2; whereupon the same may be grasped by the fingers and folded over to its operative position, as indicated in dotted lines in said Fig. 2.

15. While I have shown a cam 19 formed as a part of the annular member 16, it is obvious that the cam or abutment need not be formed as a part of an annular member as shown. I have merely adopted the 20 construction shown because it is one simple and inexpensive form of device for attaining the object in view.

Having thus described my invention, what I claim and desire to secure by Letters Patent is—

1. A tape reel comprising a support, a reel mounted thereon, means for rotating said reel, a strip of tape having one end secured to said reel, and means lying normally in the path of movement of the 30 means for rotating said reel for projecting the end of said rotating means as said reel is rotated, substantially as specified.

2. A tape reel comprising a support, a 35 reel mounted thereon, a strip of tape having one end secured to said reel, a pivoted member secured to said reel for rotating the same, and a fixed member arranged upon said support coöperating with said 40 pivoted member for projecting the latter as said reel is rotated, substantially as specified.

3. A tape reel comprising a support, a reel mounted thereon, a strip of tape having one end secured to said reel, a member 45 pivotally secured to said reel for rotating the same, and an abutment arranged upon said support adapted to engage with the free end of said pivoted member, whereby 50 to project the same as said reel is rotated, substantially as specified.

4. A tape reel comprising a casing, a reel 55 mounted therein, a strip of tape having one end secured to said reel and its other end extending out of said casing, a member pivotally secured to said reel for rotating the same, a projection on said pivoted member adapted to enter said reel, and means arranged within said casing adapted to en-

gage with the end of said projection for 60 projecting the free end of said pivoted member as said reel is rotated, substantially as specified.

5. A tape reel comprising a casing, a reel 65 mounted therein, a strip of tape having one end secured to said reel, a crank pivotally secured at one end to said reel, a handle provided at the free end of said crank and adapted to be folded into said reel, and cam means provided within said casing adapted 70 to engage with the end of said handle for projecting the free end of said crank when said reel is rotated, substantially as specified.

6. A tape reel comprising a casing, a reel 75 mounted therein, a strip of tape having one end secured to said reel, a crank pivotally secured at one end to said reel and provided at its free end with an operating handle, said reel having an opening to receive said handle when said crank is folded back upon said reel, a spring arranged within said reel adapted to engage said operating handle, when said crank is adjusted to its inoperative position, and cam 85 means arranged within said casing extending into said reel adapted to engage with the end of said handle when said reel is rotated, whereby to project the free end of said crank, substantially as specified. 90

7. A tape reel comprising a casing, a reel 95 mounted therein, a strip of tape having one end secured to said reel, a crank pivotally secured at one end to the outer side of said reel, an operating handle provided at the free end of said crank, said reel having an opening to receive said handle when said crank is folded to its inoperative position upon said reel, a spring arranged within said reel adapted to engage said operating handle when said crank is adjusted to its inoperative position, an annular member secured to the base of said casing within said reel and a projection on said annular member adapted to engage 105 with the end of said operating handle whereby to project the free end of said crank when said reel is rotated, substantially as specified. 100

Signed at the city of New York, in the 110 county of New York, and State of New York, this 14th day of October, one thousand nine hundred and thirteen.

NATHANIEL ROE.
